US00D930053S

(12) **United States Design Patent** (10) **Patent No.:** **US D930,053 S**
Suchman et al. (45) **Date of Patent:** **** Sep. 7, 2021**

(54) **DEBRIS CONTAINER**

(71) Applicant: **iRobot Corporation**, Bedford, MA (US)

(72) Inventors: **Jason Jeffrey Suchman**, Arlington, MA (US); **Douglas Dell'Accio**, Boston, MA (US); **Andrew Vincent Wolff**, Norfolk, MA (US); **Flavia Pastore**, Wakefield, MA (US)

(73) Assignee: **iRobot Corporation**, Bedford, MA (US)

(**) Term: **15 Years**

(21) Appl. No.: **29/646,574**

(22) Filed: **May 4, 2018**

(51) LOC (13) Cl. **15-09**

(52) U.S. Cl.

USPC **D15/122**

(58) **Field of Classification Search**

USPC 15/122, 132, 138, 199; 32/31, 35
CPC A01G 20/43; B08B 15/002; E01H 1/0836
See application file for complete search history.

(57) **CLAIM**

The ornamental design for a debris container, substantially as shown and described.

DESCRIPTION

FIG. 1 is a perspective view of the debris container.

FIG. 2 is a front view thereof.

FIG. 3 is a back view thereof.

FIG. 4 is right side view thereof.

FIG. 5 is left side view thereof.

FIG. 6 is top view thereof; and,

FIG. 7 is bottom view thereof.

The broken lines in the drawings depict portions of the debris container which form no part of the claimed design.
